N. Y., a corporation of New York

Application January 22, 1948, Serial No. 143,979

Term of patent 14 years

(Cl. D61—1)

To all whom it may concern:

Be it known that I, Alpheus F. Maple, a citizen of the United States, residing at Westbury, Nassau County and State of New York, have invented a new, original, and ornamental Design for a Light Meter, of which the following is a specification, reference being had to the accompanying drawing, forming a part thereof, wherein:

Fig. 1 is a front view of a light meter, showing my new design.

Fig. 2 is a side view thereof; and

Fig. 3 is a rear view of such meter.

The essential features of my design reside in the parts shown by means of full lines.

I claim:

The ornamental design for a light meter, as shown and described.

ALPHEUS F. MAPLE.
